UNITED STATES PATENT OFFICE.

ABEL THOMPSON, OF BROOKLYN, ASSIGNOR TO HIMSELF, AND DANIEL RICHARDS, OF NEW YORK, N. Y.

IMPROVEMENT IN CASKS AND BARRELS FOR OIL.

Specification forming part of Letters Patent No. 37,177, dated January 20, 1863.

To all whom it may concern:

Be it known that I, ABEL THOMPSON, of Brooklyn, in the county of Kings and State of New York, have invented, made, and applied to use a certain new and useful Improvement in Barrels or Casks for Coal-Oil, &c.; and I do hereby declare the following to be a full, clear, and exact description of the said invention, reference being had to the annexed drawings, making part of this specification in which—

Figure 1 represents a section longitudinally of my said barrel, and Fig. 2 is a partial cross-section.

Similar marks of reference denote the same parts.

The amount of leakage of coal-oil, &c., when contained in wooden barrels is so great that several attempts have been made to construct vessels entirely of metal to contain this oil, or to prepare the surface of the barrels so that the oil will not soak into the wood.

The nature of my said invention consists in a barrel or cask for coal-oil, formed of wooden staves and heads with a lining of sheet metal setting closely against the inside of said barrel or cask, by which construction the metal cylinder and wood barrel fit each other tightly; and there is no opportunity for the metal cylinder to move inside the barrel or cask while being transported, and I make use of a screw bung-hole attached to the metal cylinder and extending through the staves, and receiving a bung or screw stopper to make the same perfectly tight, but allow for easily opening the barrel or cask without the hammering now usual, and which hammering would be liable to injure the sheet-metal lining.

In the drawings, *a* is a metal cylinder (I prefer zinc) made of the required size and shape, and with the heads *b b* soldered tightly at the ends of said cylinder *a*. The cubical contents of a barrel of this cylindrical form are very easily determined.

c is a screw bung-hole formed of sheet or cast metal, attached to the case *a*, and occupying a hole in one of the wooden staves *d*, or

semicircular notches in the edges of two of the staves. These staves are of a straight cylindrical shape when placed together, so as to correspond with the metal cylinder *a*, and in order to connect the cylinder *a* more securely to the staves of the barrel I provide small sheet-metal wings *e e*, soldered upon the outside of the cylinder *a*, and running up between the staves, and said wings may be tacked to one of the respective staves before the next stave is put in place. Any desired number of these wings may be employed around the barrel.

f f are the wooden heads of the barrel, and *g g* are the ordinary hoops. The staves being thicker in the middle than toward the end, there is a sufficient exterior taper to cause the hoops to drive tightly and bring the staves firmly to each other and to the wooden heads.

The screw *c*, forming the bung-hole, is to be filled with any ordinary screw-plug turned by a wrench and provided with a washer, so as to make it perfectly tight.

What I claim, and desire to secure by Letters Patent, is—

1. Lining a barrel or cask for petroleum or coal oils with sheet metal, said lining setting against the interior of the barrel or cask, for the purposes and as specified.

2. The metal screw bung-hole *c*, attached to the cylinder *a* and passing through the staves, for the purposes specified.

3. The wings *e e*, attached to the cylinder *a* and running between the staves, for the purposes specified.

4. The staves formed as segments of a cylinder tapering on the outside and receiving the wooden heads and the hoops to form a barrel or cask, as set forth, in combination with an interior lining, whereby said barrel or cask is adapted to contain coal-oil, as specified.

Dated this 13th day of November, 1862.

A. THOMPSON.
